SURGICAL CLAMP

Filed Sept. 11, 1946

Fig. 1

UNITED STATES PATENT OFFICE

2,448,321

SURGICAL CLAMP

John A. Morrone, Jersey City, N. J.

Application September 11, 1946, Serial No. 696,225

4 Claims. (Cl. 128—346)

1

It is an object of my invention to provide a surgical clamp that supplies a positive parallel clamping action.

It is a further object of my invention to provide a surgical clamp that will materially facilitate anastomosis of any viscera or tubular organs.

It is a still further object of my invention to provide a clamp which is adaptable for use in holding anatomical parts of varying sizes and shapes.

It is a yet further object of my invention to provide a clamp that is easily adjustable by the pressure of two fingers, that having been once so adjusted remains in adjustment, that will not slip or permit slippage of the parts grasped between its clamping surfaces, and that, having once performed and completed its function, may be readily released.

It is a further object of my invention to provide a clamp that is especially adapted to receive and to doubly clamp viscera or tubular organs. Through the feature of the removable bar, my clamp is especially adapted to produce a means of mechanical union by any type of suture, canula, or button (e. g. Murphy button).

An additional object of my invention is to provide a surgical clamp that is simple in form, inexpensive to construct, easy to operate, easy to assemble and dis-assemble, and capable of being easily sterilized.

Further objects and advantages will appear from a consideration of the following description of a specific embodiment of my invention and the accompanying drawings, in which:

Figure 1 is an elevation of the surgical clamp;

Figure 2 is a side view of the removable bar;

Figure 3 is a partial view of a side member;

Figure 4 is an elevation of a sliding clamp; and

Figure 5 is an elevation of the clamp in operative position.

Referring now to the drawings in detail, my surgical clamp provides a rectangular frame which has end members 5, 6 and side members 7, 8. The end members have angularly disposed ends 9, 10, 11, 12 in which the ends of the side members 7, 8 are suitably fastened. The side members 7, 8 are preferably cylindrical. Each side member 7, 8 has a mid-section 13, 13 central thereof having a reduced diameter. This section of reduced diameter defines a seat for a removable bar 14 that spans the side members 7, 8. One end 15 of the removable bar 14 is curved to fit against and firmly seat on the mid-section 13.

2

The other end 16 of the removable bar 14 is provided with a catch 17 to enable it to be firmly seated and hold to the other mid-section 13. The catch 17 has a tail piece 18 for convenience in grasping and adjustment. A slot 19 is provided whereby it is held to the bar 14 by two screws 20, 20 or in other suitable manner. A rubber jacket 21 is provided to cover the clamping surface of the removable bar 14 whereby a soft surface is presented to minimize the possibility of damage to any viscera or organ clamped.

In addition to the bar 14, two sliding clamps 22, 22 span the frame. Each of these clamps 22 has an angularly disposed end section 23 etc. 15 which are provided with holes 24, etc., to admit the side members 7, 8. The end sections 23 are slotted 25, etc., for part the depth of the holes 24. Centrally of the clamps 22, 22, a handle 26 is provided. A U-shaped spring 27 with elongated arms is affixed to the handle 26 by a screw 28 or in another suitable manner; the ends of the arms of the spring 27 extend into the slots 25 and engage the side member 7, 8. Screws 29, 29 attach the spring 27 to the clamp 22. At 25 the screws 29, etc., slots 30 permit the movement of the springs when pressure is applied at points 31, 31, thereby disengaging the ends of the springs from the side members 7, 8. For their clamping surfaces, the clamps 22, 22 carry bars 32, 32 covered with rubber tubing 33 to present a soft, non-injurious surface to any object clamped.

The mere pressure of the springs 27, etc., on the end members 7, 8 would not be entirely sufficient to hold the clamps 22, 22 at any selected position; therefore, a series of serrations 34, 34, etc., are formed on the side members 7, 8 at the usual clamping positions. In order that the clamps may be most easily moved center-ward, 40 these serrations are formed like a buttress thread with the slanting surfaces sloping toward the outer ends of the frame and away from the center and the abutment raising vertically from the deepest part of the trough. Thus the clamps may 45 be easily slid toward the center without pressure being exerted at points 31, 31. But the abutment of the thread will prevent any out-ward or releasing movement of the clamps 22, 22 unless pressure is exerted at points 31, 31 to a sufficient 50 degree to disengage the ends of the spring 27 from the serrations 34.

The use of the device may be somewhat as follows: when it is desired to anastomose (or join) two tubular organs or viscera, the tubular 55 organs or viscera are placed alongside each other

separated by the center bar 14. The clamps 22, 22, are then moved center-ward in juxtaposition with the bar 14 until the proper amount of pressure is exerted to firmly clamp the organs or viscera in place. After surgery, the viscera is simply released by the exertion of pressure at the points 31, 31 and the removal sidewise of the clamps 22, 22. The bar 14 is disengaged from the frame and the joined viscera or organs are restored to their upper anatomical position.

I intend the foregoing description to be merely illustrative of a preferred embodiment of my invention, for many changes may be made in the materials specified, in the form, selection, and arrangement of the various parts, all of which may be within the scope of the appended claims without departing from the spirit of my invention.

I claim:

1. A surgical clamp comprising a rectangular frame, a detachable bar centrally positioned thereon, movable clamps positioned on either side of the central bar, serrations on the rectangular frame on either side of the detachable bar, and a spring associated with each of the movable clamps engageable and disengageable with the serrations.

2. A surgical clamp comprising a rectangular frame, a detachable bar centrally positioned thereon, movable clamps positioned on either side of the central bar, buttress-serrations on the rectangular frame on either side of the detachable bar, and a spring associated with each of the movable clamps engageable and disengageable with the serrations.

3. A surgical clamp comprising end members, buttress-serrated side members associated with the end members, a detachable bar centrally spanning the side members, a clamp slidably associated with the side members on one side of the detachable bar, a clamp slidably associated with the side members on the other side of the

detachable bar, a spring associated with the one clamp engageable and disengageable with the serrations, and a like spring associated with the other clamp on the other side of the detachable bar engageable and disengageable with the serrations.

4. A surgical clamp comprising end members, buttress-serrated side members associated with the end members with the buttress faces facing away from the end members, a detachable bar centrally spanning the side members, a clamp slidably associated with the side members on one side of the detachable bar, a clamp slidably associated with the side members on the other side of the detachable bar, a spring associated with the one clamp engageable and disengageable with the serrations, and a like spring associated with the other clamp on the other side of the detachable bar engageable and disengageable with the serrations.

JOHN A. MORRONE.
